UNITED STATES PATENT OFFICE.

ROBERT M. GILSON, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed June 11, 1924. Serial No. 719,333.

My invention relates to railway traffic controlling apparatus, and particularly to apparatus of the type comprising train carried governing means controlled by energy received from the trackway. More particularly, my invention relates to the trackway portion of such apparatus.

I will describe several forms of apparatus embodying my invention, and will then point out the novel features thereof in claims.

In the accompanying drawing, Fig. 1 is a diagrammatic view showing one form of trackway apparatus embodying my invention applied to a stretch of track over which traffic moves in only one direction. Figs. 2 and 3 are views showing two modifications of the apparatus illustrated in Fig. 1 and also embodying my invention. Fig. 4 is a view showing still another form of apparatus embodying my invention as applied to a single track road over which traffic moves in both directions. Fig. 5 is a view showing a modified form of apparatus shown in Fig. 2 applied to alternating current track circuits and embodying my invention.

Similar reference characters refer to similar parts in each of the several views.

Referring first to Fig. 1, the reference characters 1 and 1^a designate the track rails of a railway over which traffic normally moves in the direction indicated by the arrow. These rails are divided by means of insulated joints 2, into a plurality of track sections, only one such section, A—D, being shown in the drawing.

Section A—D is supplied with track circuit current from some suitable source of energy such as a track battery 8 connected across the entrance end of the section. Two track relays R' and R² are connected across the rails at the entrance end and exit end of the section respectively, and are responsive to current supplied by battery 8. Either or both of these track relays may be used to control traffic governing apparatus in any desired manner. As shown in the drawing a signal F located at point A is provided with an operating circuit including a front contact 51 of relay R². The signal F therefore indicates proceed when relay R² is energized and stop when this relay is de-energized.

The section to the right of point D is provided as usual with a line relay H arranged to be energized only when traffic conditions in advance of section A—D are safe. As here shown this relay is controlled by contact 50 of track relay R³, but it may in some instances be also controlled by other instrumentalities.

Means are also provided for at times supplying the trackway with alternating train controlling current. It should be here pointed out that the trackway apparatus herein shown and described is suitable for, though in no way limited to, cooperation with train carried governing means arranged to give a less restrictive indication on board the train when the stretch of track occupied by the train is supplied with train controlling current, but to give a more restrictive indication when such current is interrupted. In at least one form of train carried apparatus arranged to cooperate in this manner the governing apparatus is controlled by the trackway train controlling current through the medium of receiving apparatus located in advance of the forward axle on the train. Since the train controlling current flows in the track rails it is imperative that the source of such current be connected with the rails in advance of the train because otherwise the train controlling current would be shunted away from the receiving apparatus by the wheels and axles of the train.

I, therefore, provide a transformer T having its secondary 3 connected across the rails adjacent the exit end of the section. An impedance 5 is interposed between secondary 3 and one rail 1^a of the section in the usual manner. The circuit for primary 4 of transformer T may be traced from one terminal B of a suitable source of alternating train controlling current not shown in the drawing through front contact 6 of relay H, wire 24, primary 4 of transformer T, wire 25, back contact 7 of relay R', and back to terminal Y of the same source. It is thus plain that alternating train controlling current is supplied to section A—D only when relay R' is de-energized and relay H is energized.

The operation of the apparatus is as follows:

As shown in the drawing all the parts are

in the position corresponding to an unoccupied condition of the track. Under these conditions, current supplied to section A—D by battery 8 causes both track relays to be 5 energized. Signal F therefore indicates proceed. Relay H is also energized. The circuit for transformer T is, however, broken at back contact 7 of relay R' and no train controlling current is supplied, under 10 these conditions, to section A—D.

I will now assume that a train moving in the direction of the arrow, approaches section A—D. As this train enters section A—D, relays R' and R² both become de-energized, signal F then indicates stop, and the circuit for transformer T is then completed at back contact 7 of relay R'. Train controlling current is then supplied to section A—D by transformer T and the train 20 receives the less restrictive indication as it proceeds through the block.

If relay H were de-energized, as by the presence of a train in the section to the right of point D, and a train should enter section A—D, the de-energization of relay R' would not complete the circuit for transformer T, and the second train, being deprived of train controlling current, would receive the more restrictive indication.

30 Under certain conditions of operation, such as with a long track section and a short train, relay R' might become energized after a train had passed point A and before the train had moved completely out of the section. If this should happen the circuit for transformer T would be opened and the train would receive a more restrictive indication even if traffic conditions in advance were safe.

40 This is undesirable, and to prevent its occurrence I may arrange the apparatus as shown in Fig. 2. In this modification section A—D is provided, as before, with a track battery 8 and two track relays R' and R². Line relay H is controlled as before, and in addition I provide an auxiliary or stick relay S. When relay H is energized and relay R' becomes de-energized, a pick-up circuit is closed for relay S over which 50 current flows from terminal B', through front contact 9 of relay H, wire 10, winding of relay S, wires 11 and 12, and back contact 7 of relay R' to terminal C'. It will be plain that this circuit is closed as a train enters section A—D. Relay S is subsequently maintained in its energized condition by current through a stick circuit which passes from terminal B', through front contact 9 of relay H, wire 10, winding of relay S, 55 wire 11, front contact 13 of relay S, wire 14, front contact 15 of relay R² for the section next in advance, to terminal C'. This circuit will be closed as long as relays R² and H are energized and will prevent the de- 60 energization of relay S even if relay R'

should become energized before the train leaves section A—D. When relays S and H are both energized current is supplied to transformer T from terminal X through front contact 6 of relay H, wire 17, front 70 contact 18 of relay S, wire 19, primary 4 of transformer T, and back to terminal Y.

It should be noticed that with the apparatus illustrated in Fig. 2, after the train enters section A—D, the relay S is held in 75 its energized condition over a front contact on relay R² and that train controlling current will therefore be supplied to section A—D till the train enters the section in advance even though relay R' should become so energized. The de-energization of relay H will result in an interruption of train controlling current as in Fig. 1, thus protecting following trains.

Referring now to Fig. 3, the apparatus 85 is the same as shown in Fig. 1, except that track relay R' is here connected in series with battery 8, instead of across the rails as in Fig. 1. Relay R' is so proportioned and designed that when section A—D is unoccupied, relay R' is de-energized, but when a train enters section A—D, the increased current through relay R' causes the relay to become energized. With this modification, the current for transformer T is carried over 90 a front contact 7^a of relay R' instead of by back contact 7 as in Fig. 1. The operation of the apparatus is the same as in Fig. 1 and will be understood without further explanation. Obviously, the apparatus at 100 location A of Fig. 3 may be used with the apparatus shown at location D in Fig. 2 if desired.

In the modification shown in Fig. 4, the 105 section of track A'—D' is adapted for traffic in either direction. Relay R² is connected across the rails adjacent the exit end of the section as before. A track battery 8 and track relay R' are connected in series 110 across the rails adjacent the entrance end of the section and adjusted as explained in connection with Fig. 3 so that relay R' will be energized only when section A'—D' is occupied. A second line relay H^a is controlled so that this relay is energized only 115 when traffic conditions to the left of point A' are safe, this control, as here shown, being accomplished by contact 51 of track relay R², although other instrumentalities may enter into the control of relay H^a. 120 Secondary 3 of transformer T is connected, as before, across the rails adjacent the right hand end of section A'—D' and the circuit for the primary of this transformer is the same as in Fig. 3. To supply train controlling current for trains moving from 125 right to left, I provide a second transformer T^a located at point A' and having its secondary 19 interposed in series with battery 8 and relay R'. This transformer is ener- 130

gized when relay H^a and relay R' are both energized, the circuit passing from terminal X , through front contact 27 of relay H^a , wire 28, primary 20 of transformer T^a , wires 5 23 and 25, and front contact 7 of relay R' , back to terminal Y . When this circuit is closed train controlling current is supplied to section $A'-D'$ by transformer T^a . It is undesirable however, for this current to pass 10 through relay R' , and I therefore connect an inductive impedance 21 in series with relay R' and provide a non-inductive resistance 22 as a shunt around this impedance 21 and relay R' . The impedance 21 and the 15 winding of relay R' offer a high impedance to alternating current and a large part of the train controlling current will therefore flow through resistance 22. The ohmic resistance of the impedance 21 and relay R' is, 20 however, very much less than that of resistance 22 and hence most of the track circuit current from battery 8 will traverse the relay R' .

The operation of the apparatus for trains 25 moving from left to right is the same as in Fig. 3, and the operation for trains in the opposite direction will be understood without further explanation.

Referring now to Fig. 5, the battery 8 is 30 replaced by a track transformer designated by the reference character K and the secondary 41 of which is constantly connected across the rails adjacent the entrance end of section $A-D$ which is here shown adapted 35 for traffic moving in the direction of the arrow. The primary 40 of transformer K is constantly supplied with alternating current from some suitable source not shown in the drawing. Relays R' and R^2 are 40 responsive to the track circuit current supplied to the rails by transformer K .

Associated with track relay R^2 is a stick relay S provided with a pick-up circuit over 45 which current flows from terminal B' of a suitable source of energy not shown in the drawing, through the winding of relay S , wires 11 and 12, and back contact 7^a of relay R' back to terminal C' . This circuit is closed only when relay R' is de-energized 50 under which condition relay S is energized. The stick relay S is subsequently held in its energized condition, as long as relay R^2 is de-energized, by current over a stick circuit 55 which may be traced from terminal B ; through the winding of relay S , wires 11 and 11^a, front contact 13 of relay S , wire 14, back contact 30 of track relay R^2 , and back to terminal C' . The reference character H' designates a line relay for the control 60 of apparatus in the section to the left of A , and provided with a circuit which passes from terminal B^2 , through front contact 31 of relay R^2 , wire 32, back contact 33 of relay S , wire 34, front contact 35 of relay R' , 65 and winding of relay H' to terminal C^2 .

It follows that relay H' is energized only when relay S is de-energized and relays R' and R^2 are both energized, that is, when section $A-D$ is unoccupied. Relay H^2 is controlled by traffic conditions in the section to the right of point D in the same manner as just described for the control of relay H' by traffic conditions in section $A-D$. When relays H^2 and S are both energized current flows from terminal X of 70 a suitable source of alternating current through front contact 6 of relay H^2 , wire 17, front contact 18 of relay S , wire 19, primary 4 of transformer T , and back to terminal Y of the same source. When this 75 circuit is closed train controlling current is supplied to the rails of section $A-D$ by transformer T . In the preferred embodiment of my invention the frequency of the train controlling current is different from 80 the frequency of the alternating track circuit current and relays R' and R^2 are responsive only to track circuit current. With 85 this arrangement it is impossible for current from transformer T to pick up the 90 relays.

As shown in the drawing relays R' , R^2 , H' and H^2 are energized and relay S is therefore de-energized. Train controlling current is not supplied to section $A-D$, the 95 circuit for transformer T being open at front contact 18 of relay S . If a train proceeds into section $A-D$, relays R' , R^2 and H' are all de-energized. The closing of 100 back contact 7 of relay R' completes the pick-up circuit for relay S which in turn completes, at front contact 18 thereon, the circuit for transformer T . The train will therefore receive a proceed indication. If, 105 after the train has passed point A and before the train passes out of section $A-D$, relay R' should pick up, relay S will still be maintained in its energized condition by virtue of its stick circuit now closed over back contact 30 of relay R^2 . Should relay 110 R^2 tend to pick up, due for example to the presence of stray currents in the track rails, the opening of back contact 30 will immediately de-energize relay S and interrupt the 115 supply of train controlling current to section $A-D$. Should relay H^2 be de-energized, as by the presence of a train in the section to the right of point D , the picking up of relay S will not complete the circuit for transformer T , this circuit then being 120 broken at front contact 6 of relay H^2 . I do not in this application claim the combination of a source of alternating track circuit current connected with the rails at the entrance end of the section, and a source of 125 alternating train controlling current of different frequency connected with the rails at the exit end of the section, this combination being disclosed and claimed in my co-pending application Serial No. 732,927, 130

filed August 19, 1924, for railway traffic controlling apparatus.

Although signal F and the control thereof by relay R² are illustrated only in Fig. 1, these features may be used in connection with the apparatus illustrated in each of the other views and are only omitted from such other views for the sake of simplicity.

In each of the forms of apparatus herein illustrated and described, it should be noted that should relay R² stick in the energized position, signal F would indicate proceed, even though a train occupied section A—D. It is, however, extremely unlikely that both relays R' and R² would stick in energized positions at the same time and the de-energization of relay R' would permit train controlling current to be supplied to the section. The train will then be permitted to move through the section under a proceed indication on the train. If a following train should attempt to enter the section past the signal F stuck clear, such second train would receive a stop indication since traffic controlling current from transformer T would then be shunted away from the second train by the wheels and axles of the train already occupying the section. As soon as the first train left the section the second train would receive a proceed indication and would be permitted to continue through the section. One advantage of this feature is that instead of stopping a train automatically at a false proceed wayside signal, the train is permitted to proceed and I thereby reduce the possibility of collision due to a following train proceeding under the false signal indication, which possibility would arise if the train governing current were controlled by relay R².

One advantage of my invention is that the supply of train controlling current is normally discontinued from the section and is applied only when a train actually occupies the section.

Although I have herein shown and described only a few forms and arrangements of apparatus embodying my invention, it is understood that various changes and modifications may be made therein within the scope of the appended claims without departing from the spirit and scope of my invention.

Having thus described my invention, what I claim is:

1. In combination, a stretch of railway track, a track relay connected with the rails adjacent one end of said stretch, a source of track circuit current connected across the rails adjacent the other end of the stretch, a second track relay connected with the rails of said stretch adjacent said source, traffic governing means controlled by said first track relay, a line relay arranged to be energized only when traffic conditions in advance

of said stretch are safe, and means controlled by said second track relay and by said line relay for at times supplying train controlling current to the rails of said stretch.

2. In combination, a stretch of railway track, a track relay connected with the rails adjacent one end of said stretch, a source of track circuit current connected across the rails adjacent the other end of the stretch, a second track relay connected with the rails of said stretch adjacent said source, traffic governing means controlled by said first track relay, a line relay arranged to be energized only when traffic conditions in advance of said stretch are safe, and means controlled by said second track relay and by said line relay for at times supplying train controlling current to the rails of said stretch adjacent the first mentioned track relay.

3. In combination, a stretch of railway track, a track relay connected with the rails adjacent one end of said stretch, a signal controlled by said relay, a source of track circuit current connected across the rails adjacent the other end of the stretch, a second track relay connected with the rails of said stretch adjacent said source, a line relay arranged to be energized only when traffic conditions in advance of said stretch are safe, a transformer connected with the rails of said stretch and means including a front contact on said line relay and a back contact on said second track relay for supplying current to said transformer.

4. In combination, a stretch of railway track, a track relay for said stretch, traffic governing means controlled by said relay, a second track relay for said stretch, a line relay arranged to be energized only when traffic conditions in advance of said stretch are safe, an auxiliary relay controlled by said second track relay and said line relay, and means controlled by said auxiliary relay for at times supplying alternating train controlling current to said stretch.

5. In combination, a stretch of railway track, a track relay for said stretch, a line relay arranged to be energized only when traffic conditions in advance of said stretch are safe, a second track relay connected across the rails in advance of said stretch, a stick relay arranged to be energized when said line relay is energized and said first track relay is de-energized and to be subsequently maintained in its energized condition as long as said line relay and said second track relay are both energized, and means for supplying alternating train controlling current to the rails of said stretch when said stick relay is energized.

6. In combination, a stretch of railway track, a track relay for said stretch, a line relay arranged to be energized only when traffic conditions in advance of said stretch

- are safe, a second track relay connected across the rails in advance of said stretch, a stick relay arranged to be energized when said line relay is energized and said first 5 track relay is de-energized and to be subsequently maintained in its energized condition as long as said line relay and said second track relay are both energized, a transformer having a secondary winding connected 10 across the rails of said stretch; and a circuit for the primary of said transformer including a source of train controlling current, a front contact on said stick relay, and a front contact on said line relay.
- 15 7. In combination, a stretch of railway track, a track circuit for said stretch including a source of track circuit current and a track relay, a signal controlled by said track relay, a second relay connected with 20 the rails of said stretch, and means for supplying train controlling current to the rails of said stretch if and only if said second relay is operated due to the presence of a train in the stretch.
- 25 8. In combination, a stretch of railway track, a track circuit for said stretch including a source of track circuit current and a track relay, a signal controlled by said track relay, a second track relay connected with 30 the rails of said stretch, and means for supplying train controlling current to the rails of said stretch if and only if said second track relay is de-energized.
- 35 9. In combination, a stretch of railway track, a track circuit for said stretch including a source of track circuit current adjacent the entrance end and a track relay adjacent the exit end of the stretch, a signal controlled by said track relay, a second relay 40 connected with the rails adjacent the entrance end of said stretch, and means for supplying train controlling current to the track rails adjacent the exit end of said stretch if and only if said second relay is 45 operated due to the presence of a train in the stretch.
10. In combination, a stretch of railway track, a track circuit for said stretch including a source of track circuit current and a track relay, a signal controlled by said track relay, a second relay connected with the rails of said stretch, and means for supplying train controlling current to the rails of said stretch if and only if said second relay is operated due to the presence of a train in 50 the stretch, and traffic conditions in advance of said stretch are safe.
11. In combination, a stretch of railway track, a track circuit for said stretch including a source of track circuit current 55 and a track relay, a signal controlled by said track relay, a second track relay for said stretch, an auxiliary relay, means for energizing said auxiliary relay if and only if said second track relay is operated due to the presence of a train in the stretch, means for subsequently keeping said auxiliary relay energized until the train leaves the stretch, and means for supplying train controlling current to the rails of said 60 stretch while said auxiliary relay is energized but not when it is de-energized.
12. In combination, a stretch of railway track, a track circuit for said stretch including a source of track circuit current adjacent the entrance end and a track relay adjacent the exit end of the stretch, a signal controlled by said track relay, a second track relay for said stretch, an auxiliary relay, means for energizing said auxiliary 65 relay if and only if said second track relay is operated due to the presence of a train in the stretch, means for subsequently keeping said auxiliary relay energized until the train leaves the stretch, and means for supplying train controlling current to the track rails adjacent the exit end of said stretch while said auxiliary relay is energized but not when it is de-energized.
- In testimony whereof I affix my signature. 70
